CABLE GRIP

Filed July 2, 1929

BY

INVENTOR
Philip J. Martin,
Geo. A. Senior
HIS ATTORNEY

UNITED STATES PATENT OFFICE

PHILIP J. MARTIN, OF ELIZABETH, NEW JERSEY

CABLE GRIP

Application filed July 2, 1929. Serial No. 375,567.

The invention relates to improvements in woven cable grips. These grips are well known in the art and consist of a plurality of strands of wire or wire cord which are 5 diagonally woven or interlaced to form an open mesh capable of contracting radially when extended lengthwise and of expanding radially when contracted lengthwise.

The present invention relates particularly 10 to the draft heads or lugs for cable grips of this character and the means for attaching the cable grip to the draft heads.

The object of the invention is to provide a draft head or lug which is of extreme simplicity and economical to manufacture.

A further object is to provide a draft head and means for attaching a cable grip thereto which permits of the utmost flexibility and allows the stresses and strains developed 20 when the cable grip is in operation to be evenly distributed over all the wires or strands of the grip.

Further objects and advantages will become apparent as this specification proceeds. 25 Referring to the drawings forming a part thereof:

Fig. 1 is a side elevation of a pulling grip, the intermediate part of the grip being broken away for economy of space;

30 Fig. 2 is a view on a larger scale looking at right angles to Fig. 1, most of the cable grip being broken away.

Referring again to the drawings, the reference numeral 10 designates the woven open 35 mesh cable grip. Grips of this general type being well known it is not thought necessary to enter into a detail description at this time. The grip is formed of a plurality of diagonally interwoven strands of wire or wire 40 cord 11 which are formed into an open mesh hollow body, cylindrically shaped. The gripping action of this grip is due to the change of form of the meshes. When a pull is exerted, the meshes are elongated axially 45 and are narrowed circumferentially, thus decreasing the diameter of the grip and causing it to firmly grasp the cable.

The strands 11 at the draft end of the 50 cable grip are separated into a pair of freely formed loops 12 and 13. These loops are

formed at approximately right angles to each other and the loop 12 is preferably somewhat shorter than the loop 13. The loops are freely formed in that they are not served or wound thus allowing the stresses and strains 55 set up when the grip is in operation to be evenly distributed to all the wires or strands of the grip.

The head or lug 14 comprises an eye portion 15 to which the draw rope is attached 60 and a shank or hub 16. The shank 16 has two apertures 17 and 18 spaced apart longitudinally and having their lateral projections at approximately right angles to each other. These apertures or openings have their edges 65 rounded off or countersunk as indicated at 19.

The loop or tug 12 passes freely through the aperture 17 and the loop or tug 13 passes freely through the aperture 18, thus allowing the loops to slide freely through the apertures. This construction prevents any possibility of the cable grip pulling away from 70 the head or lug and permits of great flexibility between the head and the grip. This is particularly useful in pulling a cable 75 through uneven ducts or around bends in ducts.

In Fig. 1 the head or lug is shown in broken lines in a position it might assume in pulling a cable around a bend. With the usual type 80 of cable grip in which the mesh is firmly secured to the head or one in which the neck and eye portions are served or wound, a great strain would have to be stood by the cable grip in this position and such strains soon 85 result in the cable grip wearing out. With the illustrated construction this strain is eliminated.

In order to provide a strong rugged lug or head the portion above the shank 16 is broadened out. The edges of the eye portion as indicated at 20 in Fig. 2 flare toward this broadened out portion and are so designed 90 as to eliminate all projections that might come in contact with any obstruction in the duct while the cable is being pulled through.

As illustrated the pulling head is formed 95 of a simple integral casting. The freely formed loops are passed through the apertures during the weaving of the cable grip. 100

However, if desired, the meshes with their loops might be manufactured separately and the heads made of more than one piece so as to permit of the assembly of the heads and the 5 grips.

Such changes in detail as would occur to one skilled in the art might be made without departing from the spirit of the invention or the scope of the appended claims.

10 I claim:

1. A cable grip formed of a tubular woven mesh of wire strands brought together at the draft end into a plurality of freely formed loops and a draft head provided with a plurality of apertures through which said loops freely pass.

2. A cable grip formed of a tubular woven mesh of wire strands brought together at the draft end into a pair of freely formed loops 20 and a draft head provided with a pair of apertures through which said loops freely pass.

3. A cable grip having diagonally interwoven strands separated at one end into a 25 pair of freely formed loops and a draft head provided with a pair of apertures spaced apart longitudinally and having their lateral projections at approximately right angles to each other through which said loops freely 30 pass.

4. A cable grip having diagonally interwoven strands separated at one end into a 35 pair of freely formed loops and a draft head, said draft head being provided with an eye portion and a shank portion, the shank portion being provided with a pair of apertures through which said loops freely pass.

5. A cable grip formed of a tubular woven mesh of wire strands brought together at the 40 draft end into a plurality of freely formed loops, and a draft head, said draft head having an eye portion and a shank portion, the shank portion being provided with a plurality of apertures extending therethrough 45 said apertures being spaced apart longitudinally and formed at approximately right angles to the longitudinal axis of the cable grip and said loops freely passing through said apertures.

50 6. A draft head for a cable grip, said cable grip being formed of a tubular woven mesh of wire strands, the draft head having an eye portion and a shank portion, the shank portion being provided with a plurality of apertures extending therethrough said apertures being spaced apart longitudinally and formed at approximately right angles to the longitudinal axis of the draft head.

60 In testimony whereof I affix my signature.
PHILIP J. MARTIN.
